2 SHEETS—SHEET 2.

UNITED STATES PATENT OFFICE.

IRVING SCHENKER AND MORRIS WILAND, OF ELLENVILLE, NEW YORK.

FOUNTAIN CLOTHES-WASHER.

1,372,980.

Specification of Letters Patent. Patented Mar. 29, 1921.

Application filed January 6, 1920. Serial No. 349,688.

To all whom it may concern:

Be it known that we, IRVING SCHENKER and MORRIS WILAND, both citizens of the United States, residing at Ellenville, in the 5 county of Ulster and State of New York, have invented certain new and useful Improvements in Fountain Clothes-Washers, of which the following is a specification.

This invention relates to clothes washing 10 machines, the object of the invention being to provide a fountain clothes washer comprising a rubbing attachment for wash boards, which will simultaneously rub the clothes upon the board and operate a pump 15 thereby to force water through the clothes during the rubbing operation, and is in the form of an attachment which may be readily and quickly applied to any wash board and is comparatively simple in construction, durable 20 in use, effective in operation and easily manipulated, the washing of the clothes being obtained during the rubbing thereof by this improved attachment.

In the drawings accompanying and forming 25 a part of this specification, Figure 1 is a perspective view of the present improvement; Fig. 2 is also a perspective view with part of the mechanism exposed; Fig. 3 is a cross-sectional view taken on line 3—3 Fig. 30 2; Fig. 4 is a perspective underside view of a part of the rubbing attachment; Fig. 5 is a detail view of the pump; Fig. 6 is a side elevation of the present improvement; Fig. 7 is a perspective view of the rubbing 35 attachment, some of the parts being broken away for the sake of clearness; Fig. 8 is a detail section on line 8—8 of Fig. 9; Fig. 9 is a detail section on line 9—9 of Fig. 7; Fig. 10 is a detail plan view of the locking 40 mechanism.

Similar characters indicate corresponding parts in the several figures of the drawings.

The machine comprises in a general way a rubbing attachment adapted to coöperate 45 with the corrugated wash board and readily lifted to permit the insertion of the article to be washed between it and the board, and a pumping attachment operated by the rubbing attachment and which machine may be 50 readily attached to the side of a wash board in any suitable or desired way.

In the preferred form thereof herein shown and described, the machine comprises a pair of brackets 2 and 3. The bracket 2 55 is adapted to partially overlap or encircle the upper portion of the board, and to be

secured thereto by a screw 5 and is provided with an extended casing 4 for supporting the upper end of the piston rod hereinafter described, while the bracket 3 has a sleeve 60 portion 9 adapted to be inserted upon the leg of the side of the wash board, a suitable brace 6 connecting the two brackets at the outside of the board, the two brackets also being connected by a rigid bar or brace 7 at 65 the inner side of the board above the corrugated wash board portion 8. Detachably secured to the sleeve portion 9 of the bracket 3 is an upright bracket portion 10, to which by suitable screws and packing is attached 70 a pump cylinder 11, which is suitably inclosed by a liftable lid 12 whereby the pump mechanism may be protected from damage and is also made easily accessible. This pump cylinder is open at its lower end as 75 at 13, so that the water of the wash tub will have access thereto when the wash board is placed in the tub. The lower end of this cylinder at the inside of the opening is provided with a suitable valve 14, and within 80 the cylinder is a piston 15 secured to a piston rod 16, which is mounted for reciprocation in the bracket 10, and in the bracket 2, the upper end thereof being suitably supported in the casing 4, which is likewise pro- 85 vided with a liftable lid 17 for protecting the same, and to permit access thereto. Secured to the upper end of this piston rod and to the casing is a return coiled spring 17', which operates to shift the piston upwardly and 90 thereby the scrubbing attachment also when the same is pushed downwardly by the user. Secured to the piston rod for movement therewith and guided thereby, the rod being 95 so supported that it can oscillate in its bearings, is the rubbing attachment, which comprises a corrugated plate 18 having at one edge as the upper edge, a brush portion 19, and just under the same is a series of openings 20. The piston cylinder is provided 100 with a water outlet 21 in the form of a metal tube to which may be attached a rubber hose 22 and which hose leads to another metal tube 23 connected to the rubbing attachment, and which leads to a chamber 24 105 just above the openings 20 of the rubbing attachment whereby when the rubbing attachment is reciprocated up and down water will be pumped by means of the pump into the tube, through the rubbing attachment 110 and forced therefrom through the openings 20 on to the clothes, the rubber hose con-

necting the two metallic tubes permitting the reciprocation of the rubber in the manner described. The brush secured to the rubbing attachment is located in a casing 5 and is removable therefrom for renewal or replacement by merely lifting a lid 19' forming a part of the back of the casing as clearly shown in Figs. 7 and 9.

As stated, the piston rod rocks or oscillates and the rubbing attachment is rigidly secured thereto for swinging movement therewith and reciprocatory movement with the piston rod, and consequently the rubbing attachment may be lifted for the insertion 10 of the clothes between it and the wash board. To maintain the rubbing attachment in firm engagement with the clothes and to prevent the lifting thereof during the operation of the rubbing attachment, a 15 suitable locking means is provided. This comprises a locking cam 25 pivotally mounted in a casing 26, which is located at one end of the rubber and formed as a part thereof whereby it swings therewith. This casing 20 is likewise provided with a swinging cover 27, and this locking cam is connected with the casing by means of a spring 28 and is mounted on a small rock shaft 29 carried by the handle 30 of the rubbing attachment, 25 which handle is secured at one side to the casing 26 and at the other side to an upright support 31. The rock shaft is provided with a thumb piece 32 and with a spring 32' for returning the rock shaft to 30 its normal rocking position and thereby the cam 25. Located on the piston for movement therewith is a coöperating locking member 33 having a downwardly projecting portion carrying a suitable roller 34, which 35 acts as a guide and anti-friction device in connection with the strap or band 6, and between which and the side of the wash board the roller is shifted, as the rubbing attachment is moved up and down. When 40 the locking device 33 is in the position shown in Fig. 2, for instance, the hooked end engages the cam 25 and thus locks the rubbing attachment in contact with the clothes between it and the board. When 45 however, the thumb piece 32 is manipulated to rock the rock shaft, this swings the cam away from the hooked end whereupon as the casing 26 is provided with a slotted portion at the inner side thereof, the rubbing attachment can be raised to permit the insertion 50 of the clothes between it and the board.

To facilitate the adjustment of the rubbing attachment to accommodate different thicknesses of clothes to be washed, the 55 rubbing attachment and the casing 26, which is formed as a part thereof, is automatically adjustable, and for this purpose one end thereof is mounted upon a pair of upright posts 36 secured to the piston rod, 60 one at each side of the locking device 33, and

between projections 37 formed on the casing and the lower wall of the casing is located a pair of springs 38, which permit the rubbing attachment to automatically adjust itself to different thicknesses of articles to 70 be washed. The rubber tube 22 hereinbefore referred to connecting the two metal tubes passes through an opening in the cover 27 and this cover is also provided with a slotted portion 39 for the reception of the hooked 75 locking device 33, whereby the rubbing attachment may be raised and lowered in the manner hereinbefore described.

In operation, a thumb piece is manipulated to release the cam 25 from its coöperating locking hook 33 whereupon the rubbing attachment may be swung upward to permit the clothes to be placed upon the board. Thereupon the rubbing attachment is swung down whereupon the cam is automatically returned to its position to lock the hook and thereby lock the rubbing attachment in close contact with the article to be washed upon the board. The user thereupon grasps the handle of the rubbing 85 attachment and moves it up and down the board, which operation automatically works the pump and causes the water from the tub to pass through the tubes and be ejected on to the clothes through the openings 20 of the 90 rubbing attachment in a manner which will be readily understood.

The several swinging lids or covers are hinged in position by suitable insertible wires, such as 40, and the same means are 130 also used for locking the covers when closed. The rocking cam rock shaft is also suitably inclosed by a cover 41, which is likewise hinged in the same manner, the cover having a slot 42 for the projection of the thumb 105 piece 32 by means of which the rock shaft may be manipulated.

The various details may be more or less changed without departing from the spirit or scope of the present improvement, which 110 permits an effective and efficient washing and rubbing of the clothes simultaneously during the reciprocation of the rubbing attachment over the board.

The lower end of the lid or cover 12, 115 which covers the pump is provided with a wire netting 12' for the passage of the water to the pump cylinder, and which netting also prevents the passage of dirt and grit. The locking cam 25 carries a guide wire 25' 120 forming with the edge of the cam a guide for the hooked end of the locking member 33 when the rubbing means is swung open.

One of the details that may be readily changed is the manner in which the pump is 125 connected with the rubbing attachment. In the present instance the pump cylinder is connected by a rigid tube 21, a flexible hose 22 and another rigid tube 23 leading to the rubbing attachment, but as the rubbing at- 130

tachment is directly connected with the piston it will be obvious that instead of the tube connections just described, the pump could be directly connected with the rubbing attachment by varying the construction of the piston rod, as for instance, the piston rod could be made hollow so that the water would pass therethrough into a rigid tube, such as 23, directly connected with the piston without departing from the spirit or scope of the present improvement.

We claim as our invention:

1. A washing attachment adapted to be secured to one side of a wash board and comprising reciprocating rubbing means extending across the face of said board, and a pump extending lengthwise of and located along the outer side of said board and connected with said rubbing means at one end 15 of the latter and operated by the reciprocation of said rubbing means to force water into contact with the clothes operated upon by the rubbing means.

2. A washing attachment adapted to be secured to a wash board, comprising a reciprocating rubbing means having openings in its under face, means for adjustably supporting the rubbing means to permit it to automatically accommodate various thicknesses 30 of articles to be washed, and a pump extending lengthwise of said board at the outer side thereof and connected with said rubbing means and operated by the reciprocation of said rubbing means to force the water 35 through said openings into contact with the clothes operated upon by the rubbing means.

3. A washing attachment adapted to be secured to one side of a wash board and comprising a reciprocating rubbing means extending across the face of said board and having perforations therethrough, spring controlled means for adjustably supporting the rubbing attachment to permit it to automatically accommodate various thicknesses 40 of articles to be washed, and a pump extending lengthwise of and located along the outer side of said board and connected with said rubbing means at one end thereof and operated by the reciprocation of said rubbing means to force water through said perforations into contact with the clothes operated upon by the rubbing means.

4. A washing attachment adapted to be secured to a wash board, comprising a reciprocating rubbing means having perforations therethrough and swingingly supported relatively to the wash board, means including a cam mechanism for automatically locking it in its operative position, means for 55 adjustably supporting the rubbing means to permit it to automatically accommodate various thicknesses of articles to be washed, and a pump connected with said rubbing means and operated by the reciprocation of 60 said rubbing means to force water through

said perforations into contact with the clothes operated upon by the rubbing means.

5. A washing attachment adapted to be secured to a wash board, comprising a self-adjusting and self-locking reciprocating 70 rubbing means swingingly attached to said board and having openings in its under face, and a pump connected with said rubbing means and operated by the reciprocation of said rubbing means to force water through 75 said openings into contact with the clothes operated upon by the rubbing means.

6. A washing attachment adapted to be secured to a wash board, comprising a reciprocating rubbing means having a corrugated surface, and perforations for the passage of water therethrough, and a pump having a piston rod attached directly to said rubbing means at one side thereof and operated by the reciprocation of said rubbing 80 means to force water through said perforations into contact with the clothes operated upon by said rubbing means.

7. A washing attachment adapted to be secured to a wash board comprising a pump 90 consisting of a cylinder, a piston therein and a piston rod, means for supporting the piston rod for reciprocation relatively to the cylinder, and rubbing means secured to said rod in such manner that it is shiftable therewith and may be swung toward and from the wash board and about the axis of said rod.

8. A washing attachment adapted to be secured to a wash board, comprising a pump 100 consisting of a cylinder, a piston therein, and a piston rod, means for supporting the piston rod for reciprocation relatively to the cylinder, and rubbing means secured to said rod for reciprocation therewith and adjustable relatively to said rod.

9. A washing attachment adapted to be secured to a wash board, comprising a pump 110 consisting of a cylinder, a piston therein, and a piston rod, means for supporting the piston rod for reciprocation relatively to the cylinder, rubbing means secured to said rod for reciprocation therewith, means for locking the rubbing means in engagement with the clothes, and spring controlled means for 115 releasing said locking means.

10. A washing attachment adapted to be secured to a wash-board and comprising a reciprocating rubbing means, a pump comprising means reciprocable with said rubbing means, said rubbing means being capable of swinging movement to and from said wash-board about the axis of said second means.

11. In a washing attachment adapted to 125 be secured to a wash-board, a reciprocating rubbing means, a pump comprising means reciprocable with said rubbing means during its reciprocations, means for locking said rubbing means in its operated position and 130

- comprising a spring controlled cam, a co-operating locking member, and means for shifting said cam, said rubbing means being connected with said second means and capable of swinging about the axis thereof.
12. A washing attachment adapted to be secured to a wash board and comprising a piston rod and a pump operated thereby, manually operative reciprocating means attached to said piston rod for operating it, and means connected with said pump for ejecting the water directly into said reciprocating means, said reciprocating means comprising means for rubbing the clothes.
13. In a washing attachment adapted to be secured to a wash-board, a pump, reciprocating rubbing means connected to said pump and capable of swinging about the longitudinal axis thereof.
14. A washing attachment adapted to be secured to a wash board and comprising a pump, manually operative reciprocating means for operating it, means connected with said pump for ejecting the water on top of said board, said reciprocating means comprising means for rubbing the clothes and connected at one end with said pump, and means for permitting the swinging of said rubbing means toward and from the board about the longitudinal axis of said pump.
15. A washing machine comprising a wash board, a pump secured thereto and having

a reciprocating and rocking piston rod, and a rubbing attachment secured to said rod 35 and movable about the axis of said rod.

16. A washing machine comprising a wash board, a pump secured thereto and having a reciprocating and rocking piston rod, a rubbing attachment secured to said rod and 40 movable therewith and swingable about the axis of said rod and comprising a rubbing plate, a casing at one end thereof secured to said plate and to said piston rod, and a handle secured to said plate for reciprocating 45 it and operating the pump.

17. A washing machine comprising a wash board, a pump secured thereto and having a reciprocating and rocking piston rod, a rubbing attachment secured to said rod and 50 movable therewith and swingable about the axis of said rod and comprising a rubbing plate, a casing at one end thereof secured to said plate and to said piston rod, a handle secured to said plate for reciprocating it 55 and operating the pump, locking means for locking the plate and the casing in its operative position, said locking means being partly carried within said casing, and means carried by the handle for releasing said locking means.

Signed at Ellenville, in the county of Ulster and State of New York, this 31st day of December, 1919.

IRVING SCHENKER.
MORRIS WILAND.
